UNITED STATES PATENT OFFICE.

GEORGE B. FRANKFORTER, OF MINNEAPOLIS, MINNESOTA.

APPARATUS FOR USE IN EXTRACTING TURPENTINE AND RESINOUS MATTER FROM RESINOUS WOOD.

No. 918,989.

Specification of Letters Patent.

Patented April 20, 1909.

Application filed July 13, 1906. Serial No. 326,084.

To all whom it may concern:

Be it known that I, GEORGE B. FRANKFORTER, a citizen of the United States, residing at Minneapolis, in the county of Hennepin and State of Minnesota, have invented certain new and useful Improvements in Apparatus for Use in Extracting Turpentine and Resinous Matter from Resinous Wood; and I do hereby declare the following to be a full, clear, and exact description of the invention, such as will enable others skilled in the art to which it appertains to make and use the same.

My invention has for its especial object to provide an improved apparatus for use in extracting turpentine and resinous matter from resinous wood, and other resin containing materials, and to this end it consists of the novel devices and combinations of devices hereinafter described and defined in the claims.

The apparatus was especially designed and is particularly adapted for use in carrying out the improved "process of extracting turpentine and resinous matter from wood" disclosed and claimed in a companion application filed by me of date July 13, 1906, Serial No. 326,085.

The improved apparatus is illustrated in the single view of the accompanying drawing.

Referring to the drawing, the numeral 1 indicates a large tank preferably horizontally disposed and constructed of steel, and which, on account of one of the functions which it performs, and for the sake of definiteness in the description of the apparatus, I designate as a boiler. This boiler 1, as shown, is provided at or near its bottom with a draw-off 35 cock or faucet 2, and at its top is provided with a safety valve 3 of the usual or any suitable construction.

Located above the boiler 1 is a plurality of so-called "extraction chambers" which are adapted to contain the wood or resin containing material. As shown, these extraction chambers 4 are in the form of upright metal drums and they are provided with detachable bottoms 5 and removable upper end caps 6, which parts 5 and 6 may be detachably secured by means of threaded engagement, or by any other of the well known means for detachably securing such parts.

Vapor delivery pipes 7, 8 and 9 connect the upper portion of the boiler 1 with the upper

portions of the several extraction chambers 4. The pipes 9 terminate, within the respective extraction chambers, in annular perforated spraying sections 9^a. Return pipes 10 and 11 connect the lower or bottom portions of the several extraction chambers 4 with the lower portion of the boiler 1. Outlet pipes 12 lead upward from the top of the several extraction chambers 4 and these outlet pipes 12 are connected by an endless pipe 13. In the drawing, the several extraction chambers 4 are shown as located in a row, but in practice they might be placed in circular arrangement and, of course, any desired number of the said extraction chambers may be employed. The short pipe sections 14, as shown, connect the endless pipe 13 to the several pipes 9. Pipes 15 open into the lower portions of the several extraction chambers 4, for a purpose which will hereinafter appear. Bent tubes 16 open to the atmosphere in the upper portions of the several extraction chambers 4. These tubes, when partly filled with water or other heavy liquid, constitute water traps or seals that are normally closed.

As one means for heating the contents of the boiler 1, a closed steam conveying coil 17 leads from a suitable source of steam supply and extends along the inner lower portion of said boiler.

The numeral 18 indicates an elevated water-containing tank which is adapted to be supplied with cold water by any suitable connections (not shown). Within this tank 18 is a condensing coil 19, the upper end of which is open to the atmosphere, and to the lower end of which, as shown, are connected two pipes 20 and 21. The pipe 20 leads downward and terminates in the lower portion of the boiler 1, while the pipe 21 is directly connected, as shown, to one of the pipes 10 and hence is indirectly connected to all of said pipes 10 and to the pipe 11.

For purposes which will hereinafter appear the several pipes are provided with valves located as follows: Each pipe 9 is provided with a valve 22; each pipe 10 is provided with a valve 23; each pipe 14 is provided with a valve 24; each pipe 15 is provided with a valve 25; and the continuous pipe 13 is provided with valves 26 and 27. The valves 26 and 27 are located one at each side of each of the outlet pipes 12.

The wood in the form of chips, shavings,

excelsior or saw dust is, of course, placed in the respective extraction chambers, while the tops 6 thereof are removed and while the bottoms 5 thereof are secured in position. The 5 preferred manner for carrying out the improved process by means of the apparatus above described is as follows: One of the extraction chambers 4, let us assume the one at the left as shown in the drawing, is first 10 filled with the wood particles and the boiler 1 is partly filled with the solvent liquid, which we will assume to be petroleum ether which is a low boiling hydro-carbon compound having the property of dissolving and holding in 15 solution turpentine and resinous matter. We will now assume that all of the valves 24, 25, 26 and 27 are closed, that the valves 22 and 23 of the said first extraction chamber at the left are opened, and that all other of the 20 valves 22 and 23 are closed. We will now assume that the solvent fluid α in the boiler 1 is heated to a temperature sufficient to vaporize the said solvent liquid which, if the same be petroleum ether, requires a tempera- 25 ture above 55 degrees centigrade. The solvent vapor generated in the boiler 1 will pass upward through the pipes 7 and through the left hand pipes 8 and 9 and spraying nozzle 9 α , and will be discharged into the left hand 30 extraction chamber 4 and directly upon the wood particles γ confined in said extraction chamber. The vaporized solvent fluid upon cooling will condense within the said extraction chamber 4 and will trickle down upon 35 the wood particles and will dissolve and take into solution the turpentine and resinous matter thereof, and from said extraction chamber will flow back through the left hand pipe 10 and the return pipe 11 into the boiler 40 1. By the steam coil 17 or other suitable means, the temperature of the liquid within the boiler 1 is kept up to the boiling temperature of the said solvent liquid, so that the said solvent liquid is continuously vaporized 45 and caused to travel the course just described, through the extraction chamber noted and through the wood particles contained therein, and thence back to the boiler. The solvent liquid is revaporized by 50 a temperature which is insufficient to vaporize either the turpentine or the resinous matter and, hence, the said turpentine and resinous matter is continuously deposited in the bottom of said boiler, from which boiler it 55 may, from time to time, be drawn off through the faucet 2.

After completion of the extraction of the turpentine and resinous matter from the wood contained in the said extraction chamber 60 at the left, the valves 22, 23, 24 and 26 adjacent thereto, should be closed and the valves 25 and 27 adjacent thereto should be opened and also the valves 26 of the second or intermediate extraction chamber should 65 be opened. The opening of the valves 25

will permit the reclaiming fluid, which we will assume to be water, to run into and fill the said first or left hand extraction chamber, thereby forcing the lighter solvent fluid out of the said first extraction chamber and 70 into the second or intermediate extraction chamber. In this way, the solvent fluid left in the first extraction chamber, after the extraction of turpentine and resinous matter from the wood has been completed, is not 75 only reclaimed and saved, but is forced into the second extraction chamber. In practice, the so-called "second" or intermediate extraction chamber should be filled with the wood particles while the extraction of tur- 80 pentine and resinous matter from the wood contained in the first extraction chamber is taking place.

The crooked tubes 16 which constitute a sealing device and which normally contain 85 water or other liquid, are preferably made of glass, so that the operator can tell, by observing the upward movement of the liquid in said tube, when the extraction chamber has been filled with the water or other re- 90 claiming fluid. After the first or left hand extraction chamber has been filled with the reclaiming liquid, and the solvent liquid has been forced out of the same, the valve 27 thereof should be closed to prevent the back- 95 ward flow of the said solvent liquid. The said reclaiming liquid may be drawn off from the extraction chamber by any suitable device as, for instance, by allowing it to run backward through the pipe 15; or it may be 100 removed from the said extraction chamber together with the wood particles, when the bottom 5 of the said chamber is removed.

The above arrangement, as is evident, makes it possible to continuously carry out 105 the process of extracting the turpentine and resinous matter by always rendering available for use at least one of the extraction chambers.

Any of the solvent liquid which may be 110 converted into vapor within any of the pipes 10 or 11 may rise through the pipe 21 into the open coil 19 where it will be condensed and from thence may run back to the boiler 1 through the pipe 20.

With the apparatus above described, it is possible to have two or more of the extraction chambers in action at one time. Before the faucet 2 is opened up to draw off the turpentine and resinous matter, it is advisable first to close the valves 23 in the return pipes and to open the valves 22 in the supply pipes 9, and by the application of heat to the contents of the boiler 1 to vaporize the solvent liquid and drive the same 120 from the boiler into the extraction chambers.

What I claim is:

1. In an apparatus of the kind described, the combination with a boiler, of a plurality of extraction chambers located above the 130

same, conduits leading from the upper portion of said boiler to the upper portions of said extraction chambers, return conduits leading from the lower portions of said extraction chambers back to said common boiler, a conduit connecting the upper portions of the several extraction chambers, and other conduits opening into said extraction chambers, for delivering thereto a reclaiming fluid, and valves in the several conduits, whereby the several extraction chambers may be used successively in connection with said common boiler, substantially as described.

15 2. In an apparatus, of the kind described, the combination with a boiler, of an extrac-

tion chamber located above the same and provided with a removable cap and a removable bottom, of a conduit leading from the upper portion of said boiler to the upper portion of said extraction chamber and a return conduit leading from the lower portion of said extraction chambers back to the lower portion of said boiler, substantially as described.

25

In testimony whereof I affix my signature in presence of two witnesses.

GEORGE B. FRANKFORTER.
